UNITED STATES PATENT OFFICE.

ISIDOR LUNENFELD, OF BRANTFORD, ONTARIO, CANADA.

ASH-SIFTER.

1,351,296.

Specification of Letters Patent. Patented Aug. 31, 1920.

Application filed March 20, 1920. Serial No. 367,437.

To all whom it may concern:

Be it known that I, ISIDOR LUNENFELD, residing at 46 Colbourne street, in the city of Brantford, in the county of Brant, in the 5 Province of Ontario, Canada, have invented certain new and useful Improvements in Ash-Sifters, of which the following is the specification.

My invention relates to improvements in 10 ash sifters, and the object of the invention is to provide a simple construction of sifter which will be efficient in operation and which will be absolutely dust proof and it consists essentially of the arrangement and 15 construction of parts as hereinafter more particularly explained.

Figure 1 is a sectional view through my sifter.

Fig. 2, is an end elevation.

20 In the drawings like characters of reference indicate the various parts in each figure.

1 indicates an ash container, the top 2 of which is provided with inclined side portions 3 and 4. The end walls of the container also incline upward at their upper 25 edge to conform with the incline of the top side portions 3 and 4, terminating at each side of the center of the container so as to form a cross slot 5. Near the apex of the 30 end portions 6 of the container I provide bolts 7.

8 is a sifter which is in the form of a 35 rectangular casing having its bottom inclined downward from each end at 9 and 10 so as to form a center cross slot 11. 12 is a cylindrical portion formed integral with the portions 9 and 10 the upper portion of such cylindrical portion 12 being slotted to 40 correspond with the slot 11.

45 13 is a slot formed in the lower portion of the cylindrical portion 12. The cylindrical portion 12 is mounted at its ends upon the bolts 7 so as to swing thereon with the outer periphery of such cylindrical portion 12 remaining in contact with the side edges of the slot 5 formed by the portions 3 and 4 of the ash container 1.

14 is a flap closure for the open end of the sifter 8. 16 is a sieve secured in the sifter 50 8 so as to extend over the bottom portions 9

and 10 and the slot 11. When it is desired to sift the ashes the sifter 8 is thrown into an inclined position so that the flap 14 is presented upward. The flap 14 is secured in position by suitable fasteners 17 and these 55 fasteners which may be in the form of hooks are then swung aside and the flap 14 opened and the ashes deposited within the sifter. The closure 14 is then reclosed and the sifter 8 oscillated on the bolts 7 so that 60 the ashes are thrown from end to end of the sifter 8 upon the sieve 16. The ashes fall down through the sieve and pass through the slots 11 and 13 into the ash container 1.

It may be readily understood that by my 65 construction an absolutely dust proof joint is formed between the sifter 8 and the ash container 1 by means of the slotted cylinder 12 which, rocking in the slot 5, holds the joint closed during the rocking operation of 70 the sifter 8. When the ashes have been sifted, the sifter 8 is inclined downward so that the closure 14 is presented downward. Such closure is then opened to allow the 75 cinders falling into a suitable receptacle.

The ash container 1 is made in two portions, a body 1^x and a cover 1°. When it is desired to remove the ashes the cover and the parts carried thereby are lifted and supported from the ceiling by suitable means 80 while the ashes contained in the body of the ash sifter are emptied.

What I claim as my invention is.

A container having a convex top portion 85 provided at the apex with a slot, the side walls of said slot being formed to project above the top and to present opposed concave bearing surfaces, a sifter having the body portion thereof formed to present a slotted horizontally disposed tubular extension, said extension being disposed for oscillating movement in said slot with the outer surface thereof in sliding contact with the opposed bearing surfaces at either side of the slot, and pivots supporting the ends of 90 said extension in said slot, said pivots being positioned midway between the sides of the slot and in a plane with the opposed concaved bearing surfaces.

ISIDOR LUNENFELD.
